UNITED STATES PATENT OFFICE.

RICHARD JAHN, OF BROOKLYN, NEW YORK.

WATCH-GUARD.

1,113,011.

Specification of Letters Patent.

Patented Oct. 6, 1914.

Application filed February 4, 1914. Serial No. 816,423.

To all whom it may concern:

Be it known that I, RICHARD JAHN, a citizen of the United States, residing at Brooklyn, in the county of Kings and State of New York, have invented new and useful Improvements in Watch-Guards, of which the following is a specification.

This invention relates to safety watch guards and has for its object to provide a simple and inexpensive device of this character that may be attached to a vest or watch pocket for protecting the watch against theft.

To these ends the invention consists in the novel details of construction and combination of parts more fully hereinafter described and particularly pointed out in the claims.

Referring to the accompanying drawings forming a part of this specification in which like numerals designate like parts in all the views:—Figure 1 is a cross sectional view of a pocket showing my improved watch guard applied thereto. Fig. 2 is a perspective view of the guard detached. Fig. 3 is a perspective view of a modified form of the invention. Fig. 4 is a perspective view of a further modification.

The guard consists of a single piece of wire bent to provide a vertical shank which includes companion legs 1 and 2 bent forwardly at their upper ends 3 to provide a downwardly extending spring attaching hook 4, which hook is adapted to be sprung over the upper edge of the pocket when the guard is adjusted to position. The vertical shank which forms that portion of the guard located within the pocket, is bent at its lower ends 4' to provide right-angled and oppositely disposed end portions 5 and 6; downwardly extending portions 7 and 8; upwardly extending side portions 9 and 10 and right-angled and inwardly extending loop portions 11 and 12 which are protected by a suitable covering 13 adapted to protect the watch. These loop or guard portions are adapted to extend at right angles to the walls of the pocket and to engage the sides of the watch as shown in Fig. 1.

When in use my improved device is secured to the upper edge of the pocket by means of the spring attaching hook, the guard or loop portions engaging the sides of the watch within the pocket and with the stem of the watch, being located between the legs of the shank. When one is desirous of

removing his watch he simply inserts his fingers within the pocket and pushes the upper edge to which the guard is secured, away from his body. This movement disengages the guard or loop portions from the sides of the watch, whereby it can then be easily removed. When the watch is to be replaced the upper edge of the pocket carrying the guard is again pushed away from the wearer's body and the watch replaced.

In the modification shown in Fig. 3, a single strand of wire is bent at its middle portion as at 14—14, so as to provide the angular or shank portion 15; the wire is then bent forwardly at 16—16 and doubled upon itself so as to form the loop portions 17—17 which are similar in shape to the loops shown in the previously described form. After forming these loops, which are protected by the covering 18, the wire is bent inwardly as indicated at 19—19 and is then doubled upon itself, thus providing the attaching arms 20—20. It is to be understood that the wire is spring wire, and by virtue of the resiliency of the arms 20—20, a safety-pin 21 or the like may be engaged by the arms for the purpose of securing the guard within the pocket. The shank portion 15 which is shaped so as to form a substantial elongated frame, is adapted to extend downwardly into the pocket, and is especially adapted for retaining a money purse or the like, within the pocket and thus prevent the loss of the same therefrom.

The modified form shown in Fig. 4, is formed by bending a single strand of spring-wire angularly so as to provide a relatively rectangular portion 22; the wire is then bent obliquely as at 23—23, and upon being doubled back upon itself the angular portions 24—24 are provided. The wire is then directed upwardly and is looped so as to form the attaching arms 25—25, which are provided with a suitable pin 26 for attaching the guard within the pocket. Suitable coverings 27 may be mounted on the loops, as before described for the purpose of protecting the defacement of the watch from the wire metal.

From the foregoing it may be readily seen that by the use of my improved device the liability of theft of the watch will be greatly reduced.

It is obvious that those skilled in the art may vary the details of construction and

arrangements of parts without departing from the spirit of my invention and therefore I do not wish to be limited to such features except as may be required by the 5 claims.

What is claimed as new is:

1. A safety watch guard, comprising a single piece of wire bent to present a spring attaching portion and a pair of laterally 10 extending guard portions disposed at right angles thereto.

2. A watch guard comprising a single piece of wire having an intermediate attaching portion and laterally extending 15 guard portions disposed at right angles thereto.

3. A safety watch guard comprising a single piece of wire bent to present a vertical shank, said shank including parallel legs bent at one end to present a spring 15 attaching hook, and at their other ends bent at right angles to the shank to present oppositely disposed guard portions, and coverings mounted on the guard portions for the purpose set forth.

In testimony whereof I affix my signature in presence of two witnesses.

RICHARD JAHN.
